S. D. MOTT.
INTERNAL COMBUSTION ENGINE.
APPLICATION FILED NOV. 19, 1915.

1,355,348.

Patented Oct. 12, 1920.

UNITED STATES PATENT OFFICE.

SAMUEL D. MOTT, OF PASSAIC, NEW JERSEY, ASSIGNOR OF ONE-HALF TO ARTHUR B. SULLIVAN, OF ALLENDALE, NEW JERSEY.

INTERNAL-COMBUSTION ENGINE.

1,355,348.

Specification of Letters Patent. Patented Oct. 12, 1920.

Application filed November 19, 1915. Serial No. 62,290.

To all whom it may concern:

Be it known that I, SAMUEL D. MOTT, a citizen of the United States, resident of and whose post-office address is 130 Autumn street, in the city of Passaic, county of Passaic, and State of New Jersey, have invented certain new and useful Improvements in Internal-Combustion Engines, of which the following is a description, reference being had to the drawings forming a part hereof.

My invention relates to internal combustion engines, and more particularly to general features of construction and combination with many advantages as will herein-
15 after appear.

Among the principal objects are to produce a noiseless or silent engine with respect to the method of exhaust of the products of combustion; also a simple engine by
20 eliminating parts that would usually wear, and in present day engines cause trouble as do various forms of valves, cams, etc.; to effect complete exhaust and secure better scavenging than is usual; and other objects
25 which will be evident from the following specification.

In the accompanying drawings in which I have illustrated a particular embodiment of my invention—

30 Figure I is a vertical section of the engine at the explosion dead center.

Fig. II a vertical section at a position of the piston half way out on stroke.

Fig. III a vertical section with the piston
35 at the extreme end of the out stroke.

Fig. IV a side elevation.

Fig. V a vertical section in the plane of the crank-shaft, with piston at the outer end of its stroke.

40 Fig. VI a section of connecting-rod when the piston is at the head of the cylinder.

Fig. VII a section of connecting-rod and piston when at the extreme outer end of its stroke.

45 Fig. VIII is a side elevation and part section of piston and connecting-rod, on a plane transverse to the crank-shaft.

Fig. IX is a fragmentary section of the connecting-rod head transverse to the axis
50 of the piston-pin.

Fig. X is a section at 10—10 of the connecting-rod.

Fig. XI is a view of the end of crank case as shown in Fig. V.

Fig. XII is a top view of Figs. I, II, III and IV.

Fig. XIII is an elevation and end view of the piston in modified form.

The engine comprises the power cylinder 1, attached to the differential cylinder 2, with the crank-case 3 and crank-shaft 4, with crank-pin 5, having the hollow center or port 6 and a valve opening 7 on one side thereof.

The connecting rod 8 has the central opening 9 and crank-pin bearing 10, which may be in any suitable form, and shown as solid for purpose of illustration only; while the connecting-rod head 11 has the opening 12 passing through the head, which head is shown solid in some of the figures for the purpose of illustration only. In Figs. VIII and IX the connecting-rod ends are shown with split bearings in the usual form for the purpose of assembling.

The piston 13 has the head 14, with a central opening 15, which is an inlet port for explosive mixture. Integral with the main piston is a shoulder 16 connecting it with a differentially larger piston section 17, fitting within the supplementary cylinder 2. Into the supplementary cylinder an inlet 18 is located in the side at a point where it will be closed by the walls of the supplementary piston 17, at a certain point in the out stroke of the piston.

In Figs. VII, VIII, for purpose of illustration, only the outer portion of the piston 13, is shown. In Fig. XIII the side elevation shows the differential piston taken out of the engine, with a restricted portion 19 on the larger diameter portion, which provides a means of reducing friction between this portion of the piston and section 2 of the cylinder, and likewise permits reducing the internal space in the crank-chamber where compression is produced, as will hereinafter appear, as by varying the thickness or configuration of the internal walls of the piston.

Any suitable ignition plug or other means is indicated at 20, at the head of the cylinder. Between sections of the cylinder 1 and 2, the opposed flanges 21—22, respectively, forming the ends of these parts, are separated by any suitable spacing means, so as to form the lateral all-around opening 23, to permit the exhaust of gases as indicated

by the arrows in Figs. III and XII. This spacing may be effected by means of sleeves on the connecting-bolts 24, or in any other suitable manner.

- 5 In Fig. V, the power cylinder 25 varies from the cylinder 1 in the other views, by having projections 26 on an annular extension 27, which serve to keep the power piston head 14 in bearing with the cylinder 10 at all parts of its stroke. The spaces between the projections 26 afford an uninterrupted annular exhaust port into the annular space 28, formed on the outward stroke by the differential piston, while this annular space is open to the ultimate annular exhaust 23 at all times. The hollow connecting-rod 8 may have a section as shown in Fig. X.

It will thus be seen that in the particular form in which I have illustrated my invention, that the piston 13 is the power piston in the cylinder 1. Explosive mixture is supplied to the power cylinder through the port 12, and the hollow core 9 of the connecting-rod 8. The mixture reaches the connecting-rod through the crank-chamber formed by the cylinder 2 and crank-case 3, by means of the inlet pipe 18 which draws its mixture from any suitable carburetor or other explosive mixture producing apparatus; and when in the crank-chamber this mixture passes through the hollow core 6 of the crank-pin and through the hole 7 in the crank-pin, when the crank-pin approaches 35 and passes the end of the outer stroke, as particularly illustrated in Fig. VII. While the piston moves outward on its stroke it compresses the mixture in the crank-chamber so that a degree of compression there exists when the outer dead center is reached, which compression depends upon the relative sizes of the parts, and is predetermined by the clearance left due to the shape of the piston and crank-chamber and coöperating parts. Owing to this pressure in the crank-chamber, as soon as the outer dead center is almost reached, the port 7 registers with the hole in the connecting-rod and the compressed gases will flow through the connecting-rod and through port 12 in the head and the port 15 in the head of the cylinder, into the explosion chamber, as indicated by arrow in Figs. III and V.

After the explosion has taken place, the outward movement of the piston when approaching the dead center uncovers the lateral annular port 23, as shown in Fig. III, and at or near the extreme of the stroke the exhaust takes place. This exhaust arrangement permits maximum rapidity of exhaust by affording an outlet radially in all directions, and this outlet is relatively free compared with any of the now usual limited exhaust ports or pipes involved in current practice.

In order to preserve a continuous bearing between the cylinder and power piston walls, a modification, as shown in Fig. V, may be used. In this view a further modification has also been illustrated for use in cases 70 where it is desired to have a direct, unobstructed connection to the outer air from the cylinder. When so constructed the exhaust will pass between the projections 26, but the exhaust still will be radially in all directions and will pass into the relatively large annular chamber 28, as well as out of the lateral exhaust 23. Immediately upon passing the outer dead center, the piston moving inward, and the ports between projections 26 being closed, the shoulder 16 on the differential piston acts as an annular piston to force the products of combustion out of the annular chamber 28.

It will be seen that the inlet of fresh mixture is effected in a stream in the axis of the piston, while the exhaust has suddenly escaped radially in all directions from the sides, which arrangement facilitates to a maximum the quick exhaust of inert gases, 85 and the displacement filling the cylinder space with fresh mixture ready for the next power stroke. A few degrees after the passing of the outer dead center, the port 7 will cease to register with the opening 9 in the 90 connecting-rod, thus closing the explosion chamber and power cylinder space at the same time that the exhaust space is closed by the first operation of the return stroke, so that the entire return stroke of the piston 100 is effective in compressing or further compressing the new charge preparatory to reaching the inner end of the stroke and the next ignition. In this manner the engine operates on the two-cycle principle, with 105 crank-case compression, but in a manner which in certain forms may eliminate puppet valves, cams, etc., whereas with respect to the exhaust the construction is such as to afford a maximum, free, quick exhausting of 110 the products of combustion with the attendant advantage of elimination of the noise. This rapid exhaust, free so far as possible, may be compared with the burning of powder when not confined, which is free from 115 detonation, whereas powder confined and exploded, with a small exit for the increased pressure, produces a loud report.

While in Figs. VIII, IX and X, particular forms of connecting-rod and connecting-rod 120 bearings have been shown, these may be made in any suitable manner to meet the requirements of construction confronting any designer; and as to other details they are in the main shown in conventional form, 125 with the details of crank-shaft bearings and other details eliminated as such may be made as usual. The piston section 17 is shown recessed so as not to interfere with the crank-shaft, while at the same time extending at 130

other parts of its circumference the desired distance to close the inlet 18, to effect compression in the crank-chamber.

As shown in Fig. V, the differential piston 5 on its outward movement, considering particularly high speed, will tend to create a slight vacuum in the annular cylindrical space 28, or at least will effect a suction in proximity to the exhaust port, so that upon 10 the opening of the exhaust port the gases are drawn into the annular chamber, thereby increasing the efficiency of exhaust and aiding in the scavenging of the cylinder. On the return stroke these gases will be forced 15 out of the annular exhaust opening 23.

The same effect in the varying degree is realized in the form as shown in Figs. I, II and III. The annular chamber or cylinder space of the differential piston forms an 20 exhaust chamber with more or less rarefaction of air at the time the exhaust port opens, and thereby aids in drawing out the exhaust, or at least minimizing or reducing the resistance to the exhaust, having 25 corresponding effect as to the muffling and scavenging. This also, as is well known, increases the efficiency of the engine by reducing or eliminating any back pressure at the exhaust port and goes further when so designed as to create an actual vacuum or suction, thereby producing a marked increase 30 and efficiency for given dimensions of engine.

Various changes may be made in dimensions and arrangement when embodying my 35 invention in any specific design or size, and while shown with the explosion chamber at the bottom, this may be reversed or the engine positioned horizontally, or in any 40 other manner desired.

Without confining myself to the particular form herein shown and specifically described, what I claim and desire to secure by Letters Patent is:

45 1. An internal combustion engine comprising an explosion chamber and exhaust port in the sides of said cylinder uncovered by the piston substantially at the end of the out stroke, said port comprising substantially a continuous annular opening circumferentially encircling the base of the cylinder, a piston rod, and an inlet through the piston and through the piston rod, as and for the purpose described.

55 2. An internal combustion engine, a power cylinder, a power piston, a differentially larger section on said piston and a supplementary cylinder fitting said differential portion, an inlet port for mixture controlled 60 by said differential section of the piston and a controlled mixture supply from the crank-chamber through the piston to the working cylinder, a circumferential exhaust port adjacent to the differentially larger section of 65 the cylinder.

3. An internal combustion engine, a power cylinder, a power piston, a mixture inlet centrally located in said piston, an exhaust comprising a substantially continuous circumferential port opening directly to the 70 surrounding air at the base of said power cylinder, an annular piston coöperating with said power piston and coöperating with a supplementary cylinder to form an annular space and connections between said outlet port and said annular space. 75

4. An internal combustion engine having an inclosed crank chamber, a mixture inlet for said crank chamber, a power piston, a hollow connecting rod having an outlet into 80 the combustion chamber, a crank pin having a mixture passage opening into the crank chamber and a port in said crank pin controlling the connection to the hollow connecting rod and closed and opened by the 85 rotation of the crank.

5. An internal combustion engine, comprising an inclosed crank-chamber, a piston, a projection on and coacting with said piston and crank-chamber to compress the mixture in the crank-chamber and to control the inlet of the mixture to the chamber, a hollow connecting rod, a port connection between the crank end of the connecting rod and the crank-chamber and from the other end of 90 the connecting rod to the combustion-chamber, and parts associated with the crank-shaft coacting therewith, whereby a compressed charge in the crank-chamber is admitted under pressure to the explosion-chamber at a predetermined time near the outer dead-center of the crank. 100

6. An internal combustion engine, a power cylinder, a supplemental cylinder, a power piston, a concentrically arranged greater 105 supplementary piston, rigid connections between the power cylinder and supplementary cylinder affording spaced relation therebetween to afford a substantially complete circumferential port at the base of the power cylinder, whereby a radial exhaust is permitted in all directions at the extreme outward stroke of the piston, and a guide member to assure engagement between the piston and the power cylinder when said circumferential port is passed. 110

7. A muffler or silencer for internal combustion engines, comprising an annular exhaust port uncovered by the power piston on its out stroke and adapted to permit the 120 instantaneous exit of the gases directly to the surrounding atmosphere and an annular chamber contiguous with said annular exhaust port and coöperating therewith to facilitate the exhaust, substantially as described. 125

8. A muffler or silencer for internal combustion engines, comprising a port in the cylinder with relatively unimpeded connection to the surrounding atmosphere and a 130

power piston adapted to open said port near the end of the power stroke and a differential piston part actuating adjacent to said port for creating a suction in the vicinity of said exhaust.

9. In an internal combustion engine, an exhaust port at the side of the power cylinder opened by the piston itself at the outer throw of the piston permitting free egress 10 of exhaust gases directly to the surrounding air and free ingress of air, a chamber in proximity and having a connection with said

free exhaust and means for suitably varying the size of said chamber to coöperate for the quick exit of gases.

In testimony whereof I have signed my name to this specifacaton, in the presence of two subscribing witnesses, this 13th day of November, 1915.

SAMUEL D. MOTT.
